UNITED STATES PATENT OFFICE

2,642,284

SHEET REGISTERING APPARATUS

Headley Townsend Backhouse, Sunningdale,
EnglandApplication November 9, 1949, Serial No. 126,268
In Great Britain November 12, 1948

1 Claim. (Cl. 271—60)

1

The invention relates to sheet registering apparatus of the kind which may constitute part of a printing machine or part of a machine for separating sheets from a pile and which embodies a lay-board or front plate on to which sheets of paper, card or the like are fed in a continuous stream of partly overlapping sheets, and means for engaging the front edge and, it may be, also the side edge, of each sheet in turn, to effect registration thereof and from which board or plate the sheets are transferred individually after registration to a printing or other machine operating on single sheets.

It is desirable in apparatus of the above kind, and with a view to reducing the interval between the removal of successive sheets with, in the case of a rotary printing machine, a corresponding reduction in the ineffective parts of the circumference of the cylinder to which the sheets are transferred, to effect the registration of each sheet during the removal of the preceding sheet from the lay-board and it is known for this purpose to provide front and side registering devices operating beneath the sheet being removed, the sheets being supplied to the lay-board in partly overlapped relation. In order that devices operating in this way may be effective it is necessary to ensure that the succeeding sheet does not adhere to the sheet being removed and is not carried into the printing or other machine with the latter sheet.

My prior United States applications Nos. 62,249 and 62,251, both filed November 26, 1948, application Serial No. 62,249 having issued as U. S. Patent Serial No. 2,605,103, and application Ser. No. 62,251 having been abandoned, I have described a scraper device constituting simple means for engaging the leading edge of each sheet as it approaches the registering position and to separate that edge from the overlying sheet being removed. It is an object of the present invention to improve the scraper device described in the above-mentioned prior specifications. With the above object in view the invention provides sheet registering apparatus of the kind described above which has a scraper device arranged to move against the direction of the flow of sheets while scraping the undersurface of the sheet being removed and in such timed relation with the feeding of the sheets that the device will meet and engage the front edge of a succeeding sheet as it approaches the registering position, the scraper device being arranged to engage the said front edge to separate the edge from the overlying sheet and which apparatus also has the feature that the scraper device incorporates a

10 15 20 25 30 35 40 45 50 55

2

feeler, movable with the device, for detecting the non-arrival or late arrival of a sheet at the device.

In the preferred arrangement of the present invention the scraper device also constitutes a front lay.

The feeler may be arranged for movement relative to the body of the scraper device by a sheet arriving at the correct time and the apparatus may include a sensing member for determining whether the feeler has been moved as aforesaid and if it has not for stopping the apparatus or operating the warning device.

The scraper device itself may constitute the front lay or the feeler may constitute the gauge face or part of the gauge face of the front lay scraper device and be movable by the front edge of a properly presented sheet up to a stop on the device which determines the lay position of the face.

One specific construction of sheet registering apparatus according to the invention and incorporated in a sheet feeding machine embodying the features of the machine described in my United States application Ser. No. 62,251, filed November 26, 1948, application Serial No. 62,249 having issued as U. S. Patent Serial No. 2,605,103, and application Ser. No. 62,251 having been abandoned, will now be described by way of example and with reference to the accompanying drawings in which:—

Figure 1 is a perspective diagrammatic view of the feeding machine and also shows parts of an associated sheet separator and of a printing machine.

Figure 2 is a side view of the apparatus.

Figure 3 is a view in the direction III—III in Figure 2.

Figure 4 is a rear view of the apparatus.

Figure 5 is a plan of the apparatus.

Figure 6 is under plan of the apparatus and

Figure 7 is a section on the line VII—VII in Figure 4.

The apparatus embodies a lay-board 6 on to which the sheets 7 are fed, by tapes 1 driven from roller 2, as a continuous stream of partly overlapped sheets and from which the sheets are taken individually, after front and side registration, by swinging grippers 12 by which they are transferred to grippers on the drum 13 of a printing machine. Spaced apart along the front edge of the lay-board there are a number of angular scraper devices 11. Each of these devices consists of a member having two arms 11a, 11b, at right angles and each device is attached at the end of the arm 11a (later referred to as the gauge arm) to a shaft 10 supported for oscillation

55

below the front edge of the lay-board and parallel to that edge. The members are movable, by oscillation of the shaft, from a position in which the arm 11b (later referred to as the scraper arm) extends upwardly towards the underside of a sheet 7 being removed from the lay-board to a position (see Figure 7) in which the scraper arm lies above and substantially parallel to the front edge portion of a succeeding sheet, the movements of the member as aforesaid being in a direction against the movement of the sheets and being so timed that the free end of the scraper arm scrapes the underside of the sheet being removed as the next sheet approaches the register position (see Figure 2). In its final position (Figure 7) the scraper arm lies parallel to the upper surface of the lay-board and serves as a smoother for the front edge of the sheet.

In this example two of the scraper devices are provided with feelers, the two devices so provided being positioned adjacent opposite sides of the lay-board. Each feeler is constituted by a lever 30 approximately parallel to the gauge arm and pivoted about the shaft 10 supporting the scraper device and having its free end received within a hole 35 in the scraper arm of the device, which limits the movement of the lever. A light spring 36 tends to move the lever away from the gauge arm in the direction to meet the front edge of an oncoming sheet (i. e. in the clockwise direction as viewed in Figure 7). The lever has a hook-like tail 31 arranged to make interlocking engagement with a hook 32 on a sensing arm 33 when the lever has not been moved by a sheet (i. e. when the lever is in the chain line position in Figure 7) and thereby to prevent movement of the sensing arm which is arranged thereupon to cause operation of a warning device or stoppage of the apparatus. The sensing arm is carried on a second shaft 40 mounted below the lay-board and parallel to the first mentioned shaft 10. This second shaft is arranged for oscillation in such timed relationship with the feeding of the sheets that the sensing arm 33 makes a downward stroke immediately after the time at which a sheet should make contact with and move the feeler. Thus, if the feeler has been so moved the arm is freed and able to make its downward stroke whereas if the feeler has not been moved the hook on the tail 31 of the lever engages the hook 32 on the arm and prevents such movement of the sensing arm. The shaft 40 carrying the sensing arms is oscillated in timed relation with the machine by any suitable means. It is to be appreciated that the feelers move with the scraper devices during the oscillation of the devices.

The scraper devices may constitute the sole registering means for the sheets or additional register stops may be incorporated in the swinging grippers.

The apparatus forming the subject of the above example includes air nozzles 20 and means for supplying air to the nozzles.

The present invention may also be applied to the printing machine described in my United States application Ser. No. 62,649, filed November 26, 1948.

I claim:

5 In a sheet feeding machine of the kind in which a succession of partly overlapped sheets are fed by conveyor means and as a continuous stream onto a layboard to a position where each sheet in turn is brought to rest and registration of the sheet is effected against front lays and from which board the sheet is then removed while the underlying sheet is approaching the registering position, the combination of a scraper device arranged to operate below each sheet as it is removed from the lay board to scrape the lower face of the sheet, to engage the leading edge of a succeeding sheet as it approaches the lays to separate that edge from the sheet being removed, which scraper device consists of a member having two arms at an angle and pivotally supported about the free end of one of the arms below the layboard for oscillation about an axis parallel to the leading edge of the sheet to be engaged from a position in which the other arm (later referred to as the scraper arm) extends upwardly towards the underside of the sheet being removed to a position in which the scraper arm lies above and substantially parallel to the front edge portion of the succeeding sheet, the movement of the device as aforesaid being in a direction against the movement of the sheets and being followed by a return movement to the initial position, means for oscillating the scraper device as aforesaid and in such timed relation with the feeding of the sheets that the free end of the scraper arm scrapes the underside of the sheet being removed as the next sheet approaches the lays and the scraper arm reaches the limit of its movement just before the sheet reaches the lays, a feeler which is incorporated in and movable with the scraper device and which is also movable relative to the scraper device by a sheet arriving at the correct time, and a movable sensing member for determining whether the feeler has been moved as aforesaid and if it has not for stopping the machine or operating a warning device.

50 HEADLEY TOWNSEND BACKHOUSE.
